UNITED STATES PATENT OFFICE.

ALEXANDER R. LINN AND WILLIAM F. LINN, OF DETROIT, MICHIGAN.

DESIGN FOR TEA-CADDIES.

Specification forming part of Design No. 7,389, dated April 21, 1874; application filed March 24, 1874.
 [Term of Patent 7 years.]

To all whom it may concern:

Be it known that we, ALEXANDER R. LINN and WILLIAM F. LINN, of Detroit, in the county of Wayne and State of Michigan, have invented a Design for a Tea-Caddy, of which the following is a specification:

The nature of our design is fully represented in the accompanying photographic illustration, to which reference is made, the invention relating more particularly to a caddy used by retail dealers for containing tea or ground coffee.

A represents the body of our can, having a curved front, A', of the particular configuration shown, which front does not extend up the full height of the sides and back, but is finished by a curved slope, B, to the top C, which is pagoda-shaped, with a square base, the caddy having greater depth from front to rear than width; the pagoda-top is surmounted by an acorn or other finial ornament. In the

slope B, which somewhat resembles the face of a Mansard roof, is an opening, over which is hinged a door, B', which gives access to the interior. The face of the caddy is ornamented with Chinese or oriental scenery or portraits, and the entire body is japanned with any desired color.

We do not claim any particular design or picture for ornamenting the front or top of the caddy, the shape or form of the caddy alone being new.

What we claim as our invention is—

The tea-caddy described, having the curved front A, the curved slope B, and the pagoda-top C, with a square base, as shown and described.

ALEXANDER R. LINN.
 WILLIAM F. LINN.
